UNITED STATES PATENT OFFICE.

J. M. TROWBRIDGE, OF UNITED STATES ARMY.

IMPROVED CANTEEN.

Specification forming part of Letters Patent No. 40,655, dated November 17, 1863.

To all whom it may concern:

Be it known that I, JOSEPH M. TROWBRIDGE, of the United States Army, have invented a new and Improved Canteen; and I do hereby declare the following to be a full, clear, and exact description thereof, reference being had to the accompanying drawings, making part of this specification.

The object of this invention is to furnish each soldier with a convenient and ready means of preparing coffee or soup during pauses on the march or on picket or in bivouac, independently of the company supply-trains, or in other words, to enable each soldier to conveniently carry all the cooking apparatus that is absolutely necessary.

Figure 1 exhibits a canteen in the closed condition. Fig. 2 represents the parts of the canteen detached and ready for use.

A is the bottle for carrying water on the march. It is made to fit snugly within the boiler hereinafter described, either by flaring upward in the manner represented or by any other approved device.

B represents my boiler, formed to receive and securely hold the bottle A, as seen in Fig. 1, or to allow of the easy separation of the latter, as seen in Fig. 2.

C C' are ears to receive a bail, L, by which the boiler may be suspended over a fire or

conveyed from spot to spot without spilling the contents.

D is a side handle to facilitate the use of the boiler as a cup or bowl.

E E' are rings or ears for a sling, O, by means of which the entire canteen, when closed, may be suspended upon the person. An obvious advantage of this arrangement is the easy access to the water-bottle, it not being necessary to unsling the same, as with the common canteen.

My boiler serves all the purposes of the cup ordinarily carried by the soldier, and in addition thereto forms a convenient pot for boiling coffee, soup, or other viands.

I claim as a new article of manufacture—

The cooking-canteen, composed of a bottle, A, and the inclosing boiler B C C' D E E', or their equivalents, the whole being so adapted and arranged as to combine the functions of a canteen with those of a cup and boiler, within convenient and portable limits, substantially as set forth.

In testimony of which invention I hereunto set my hand.

J. M. TROWBRIDGE.
